DESIGN FOR A SPRAY HEAD

Hans Werner, Verona, N. J., assignor to Gifford
D. Davis, South Orange, N. J.

Application February 5, 1941, Serial No. 98,757

Term of patent 14 years

To all whom it may concern:

Be it known that Hans Werner, a citizen of Germany and resident of Verona, in the county of Essex and State of New Jersey, has invented a certain new, original, and ornamental Design for a Spray Head, of which the following is a specification, reference being had to the accompanying drawing, forming a part thereof.

Figure 1 is a plan view of a spray head showing my new design.

Figure 2 is a view in side elevation of a spray head shown in Figure 1.

Figure 3 is a view looking upwardly towards the bottom of the spray head shown in Figures 1 and 2.

Figure 4 is a fragmentary cross-sectional view on line 4-4 of Figure 3 and shows the contour of the teats.

I claim:

The ornamental design for a spray head, as shown.

HANS WERNER.
